CARTON FOR RADIO TUBES

Christian Mowry Knaur, Williamsport, Pa.

Application December 15, 1937, Serial No. 180,006

5 Claims. (Cl. 229—6)

This invention relates to certain new and useful improvements in cartons for radio tubes and the like, the object being to provide a carton formed of two members, one telescoped within the other in order to allow the inner member to move in respect to the outer member so that the tube carried thereby can be extended to permit the tube to be examined and tested and yet prevent it from being removed so as to prevent the bootlegging of an inferior product.

Another object of my invention is to provide a carton which is exceedingly simple and cheap in construction, each member being formed of a single piece of material bent into its proper shape and secured together in such a manner that one is free to move in respect to the other and yet is prevented from being extended to such an extent that the tube carried thereby can be removed.

Another and further object of the invention is to provide a carton having three supporting means for the tube, whereby the tube is held firmly so as to prevent the same from being injured in shipping.

Other and further objects and advantages of the invention will be hereinafter set forth and the novel features thereof defined by the appended claims.

In the drawing,

Figure 1 is a plan view of a blank from which the inner member of my improved carton is formed;

Figure 2 is a longitudinal section through the complete carton showing the tube in position therein;

Figure 3 is a longitudinal section through a portion of the carton showing the inner member moved outwardly in position so that the tube can be inspected and tested;

Figure 4 is a perspective view of the inner member detached; and

Figure 5 is a detail perspective view of a portion of the inner member showing the yieldable tongue.

My improved construction of carton is formed of an outer tubular member A and an inner tube supporting member B, each formed of a single piece of material, the inner member being telescoped within the other member.

The outer member is formed of a rectangular piece of material, such as cardboard or the like bent into tubular form having its ends overlapped and glued together. The tube thus formed is substantially rectangular in cross section and it is, of course, understood that it can

be formed of any shape desired without departing from the spirit of my invention.

The inner member B is formed of a strip of material, such as cardboard or the like, scored transversely on lines 1, 2, 3, 4, 5 and 6 and bent into an oblong shaped body having opposing walls 7 and 8, end members 9 and 10 and a partition 11. The wall 7 is provided with a slit 12 to receive a locking tongue 13 formed on the end of the strip for locking said body in its bent shape. The wall 8 is provided with side flaps 14 and 15 bent inwardly as shown on scored lines to form opposing side wall portions and the end members 9 and 10 are provided with flaps 16, 17, 18 and 19 bent outwardly on scored lines as shown in Figure 4 to position and hold the body within the outer member A. The partition 11 is provided with a flap 20 bent at right angles thereto on scored lines and adapted to engage the end member 10 for positioning the partition within the body.

The end members 9 and 10 and the partition 11 are apertured to receive and support a radio tube C to prevent it from being injured in shipping as it will be noted that the partition surrounds the tube intermediate its ends to hold the tube properly centered within the carton and that the side walls and the side flaps form walls for protecting the tube.

The wall 8 is cut to form a substantially T-shaped tongue 21, the stem of the tongue being scored transversely as shown at 22 in Figure 1 and bent back upon itself as shown in Figure 4 and the head of the tongue is connected to the outer member A by a rivet or the like 23 as shown in Figures 2 and 3. The yielding portion 22 is formed by a plurality of scores arranged parallel to one another and limits the movement of the inner member within the outer member a predetermined distance sufficiently to allow the tube carried thereby to be extended for testing and to be withdrawn to a position so that the ends of the side flaps of the end leaves will be flush with the ends of the outer member A, as shown in Figure 2.

By constructing the carton of two members, one telescoped within the other and each member being formed of a single piece of material, I am able to manufacture a carton very cheaply which has all of the advantages of cartons now in use to prevent the bootlegging of an inferior product and yet can be manufactured much cheaper and has many advantages over the other constructions in view of the fact that it supports the radio tube more firmly to prevent the

same from vibrating in shipping or being displaced from the end members.

Assuming that a radio tube is in position within the carton as shown in Figure 2, when it is desired to test or examine the tube, by exerting pressure on the end member of the tube, the inner member will slide within the outer member so as to expose the tube as the yielding portion 22 of the tongue allows the inner tube to move within the outer tube a predetermined distance which is sufficient to examine the tube and yet prevent the tube from being removed.

What I claim is:

1. A carton for radio tubes and the like consisting of two members, one member telescoped within the other, each member being formed of a single piece of material, the inner member having a tongue cut out of one wall thereof and bent back upon itself and permanently connected to the outer member to allow said inner member to move a predetermined distance within the outer member.

2. A carton for radio tubes and the like consisting of two members, one member telescoped within the other, each member being formed of a single piece of material, the inner member having a tongue cut out of one wall thereof and bent back upon itself and permanently connected to the outer member, a portion of said tongue being yieldable to allow said inner member to move a predetermined distance within the outer member.

3. A carton for radio tubes and the like com-

prising an outer tubular member, an inner tube supporting member movably mounted therein formed of a single strip of material bent into oblong shape having apertured ends and an apertured partition to receive and support a tube and a tongue cut out of one wall of said inner member having a permanent connection with the outer member for limiting the moment of the inner member within the outer member.

4. A carton for radio tubes and the like comprising an outer tubular member and an inner tube supporting member movably mounted therein, the inner member being formed of a single strip of material folded transversely into oblong shape to form ends and a transverse partition, the ends and partition being apertured to receive and support a radio tube, a tongue cut out of one wall of the inner member and bent back upon itself adjacent its connection with said wall and extending outwardly beyond the adjacent end and connected to the outer member to form a yieldable connection between said members to limit the movement of the inner member within the outer member.

5. A carton for radio tubes and the like comprising two members, one telescoped within the other, the inner member having a tongue cut out of one wall thereof and permanently connected to the outer member for limiting the movement of the inner member within the outer member.

CHRISTIAN MOWRY KNAUR.
